UNITED STATES PATENT OFFICE

CHARLES J. TRAVERS, OF PORT WASHINGTON, WISCONSIN, ASSIGNOR TO
GILSON MANUFACTURING COMPANY, OF SAME PLACE.

DESIGN FOR A CHAIR-HUB PLATE.

SPECIFICATION forming part of Design No. 35,111, dated September 17, 1901.

Application filed August 10, 1901. Serial No. 71,659. Term of patent 14 years.

To all whom it may concern:

Be it known that I, CHARLES J. TRAVERS, a citizen of the United States, residing at Port Washington, in the county of Ozaukee and State of Wisconsin, have invented and produced a new and original Design for a Chair-Hub Plate; and I do hereby declare the following to be a full, clear, and exact description of the same, reference being had to the accompanying drawings, forming a part thereof.

In the said drawings, Figure 1 is a plan view, and Figs. 2 and 3 are sectional views taken, respectively, on the planes indicated by the lines 2 2 and 3 3 of Fig. 1, with the plate in an inverted position, of a chair-hub plate embodying my new design.

My design relates to the new and original shape or configuration of the article.

The leading or essential feature consists in the unitary design for a chair-hub plate made the subject of illustration, comprising the shape of the body A, formed with two opposed pairs of lateral extensions B B B B, with a continuous outwardly obliquely flaring projecting border C, which at the outer edges of the said extensions B is formed on rounded

convex lines, and at the edge of the body A, between each extension B, the said border C is formed on rounded concave lines merging into the just-named rounded convex lines. 30 At the center the body A is formed with a circular opening having a rounded flaring annular wall or edge D, and each extension B is formed with a hollow truncated conical projection E.

Minor features of said design comprise the extension of the outer ends of said truncated cones E to a plane beyond that of the plane of the described continuous outer border C and the formation of the edges of the said border 40 and the annular wall D on the same plane. 35

Having thus described my invention, what I claim as new, and desire to secure by Letters Patent, is—

The design for a chair-hub plate, substantially as herein shown and described. 45

In testimony whereof I affix my signature in presence of two witnesses.

CHAS. J. TRAVERS.
